UNITED STATES PATENT OFFICE.

RUFUS FRANKLIN CARNES, OF ELDIDGE, ALABAMA, ASSIGNOR OF ONE-HALF TO JOHN H. BANKHEAD, JR., OF JASPER, ALABAMA.

SELF-CLOSING RAILROAD-SWITCH.

SPECIFICATION forming part of Letters Patent No. 619,135, dated February 7, 1899.

Application filed July 9, 1898. Serial No. 685,551. (No model.)

To all whom it may concern:

Be it known that I, RUFUS FRANKLIN CARNES, of Eldridge, in the county of Walker and State of Alabama, have invented a new and useful Improvement in Self-Closing Railroad-Switches, of which the following is a specification.

It is often the case that a train-crew or track-man forgets to close a switch after opening it and goes away leaving it open or thrown to siding. Should a train on the main track come from the same direction, (as the one that passed off the siding and left the switch open,) said train on the main track splits the switch and is itself wrecked. Should a train on the main track come in the opposite direction, it runs on the siding, and if any cars are on the siding the train collides with them, and if the train is moving fast there is damage to the extent of thousands of dollars and many lives are lost. It is to prevent just such accidents that my invention is designed, and it proceeds by making the closure of the switch (after being opened) independent of the memory or thought of the switchman by providing automatic self - closing devices arranged to act within a predetermined time to automatically close the switch at the expiration of a definite interval of time, so that even if the switchman forgets and leaves the switch open it will at the expiration of its interval of time automatically close itself.

My invention comprises a motor for closing the switch, which is set into action by the movement of the switch-lever in opening the switch, combined with an escapement mechanism arranged to close the switch after a definite interval, as will be hereinafter more fully described, with reference to the drawings, in which—

Figure 1 is a plan view of the switch, with the switch-stand shown in horizontal section. Fig. 2 is a vertical section on line 2 2 of Fig. 1. Fig. 3 is a side elevation of the switch-stand, taken from the lever side. Fig. 4 is a side elevation from the opposite side to Fig. 3. Fig. 5 is an inside elevation of the switch-stand, looking in the direction of the arrow in Fig. 1. Figs. 6 and 7 are details in perspective of the interior mechanism, and Fig.

8 is a sectional perspective view of a part of the switch.

In the drawings, Fig. 1, A A represent the two rails of the main track, and B B the two rails of a siding.

55

A' and B' are the two switch-rails, which are pivoted at their ends a' b' and taper to a wedge end at the other end and are connected by transverse bars a², so as to be held parallel as they swing laterally about their pivots a' b'. When the switch A' B' is thrown to the left, as indicated in dotted lines in Fig. 1, the main track is open or disconnected to admit cars onto the siding, and when the switch-rails are thrown to the right the main track is continuous or closed and the siding is disconnected. The lateral adjustment of these switch-rails is effected by a horizontal rod C, extending into the lower part of the switch-stand S. This stand is a sheet-metal box made in pieces and connected by bolts which cannot be tampered with from the outside, and has also on one side a hinged door D to give access of switch-tender to the interior.

60

In suitable bearings in the lower part of the switch-stand there is journaled a horizontal main shaft E, which extends through the side of the box and is provided with a rigidly-attached hand-lever E'. This shaft within the box is also provided with a semi-circular gear-wheel E² and a drum E³, Fig. 7, beside it, upon which is wound a cord, wire, chain, or other flexible connection a, and the other end of which is attached to a spring-arm b, so that when shaft E is rotated in one direction it winds up the cord on the drum and puts the spring-arm under tension, which spring-arm will then tend to rotate the semi-circular gear in the opposite direction.

65

Just above the shaft E and parallel with it there is another horizontal shaft F, journaled in bearings in the framework and having rigidly attached to it a small gear-wheel f, Fig. 5, adapted to be engaged by the semicircular gear E², and also a large toothed escapement-wheel F'. Just above this escapement-wheel and lying in its vertical plane there is arranged a rock-shaft G, which is provided at a point near its middle and tangential to the escapement-wheel with two inclined lugs or 70

bearings g g' , which alternately engage with the teeth of the wheel and allow the latter to pass one at a time with an intermittent motion. On the end of this rock-shaft there is 5 rigidly fixed a swinging pendulum H , extending both above and below the center of oscillation and provided with adjustable weights h h , which may be moved up and down on the pendulum-arms to cause their oscillation 10 to be faster or slower, as may be desired.

On the main shaft E , Fig. 7, there is a cam 15 E^4 , which bears against the bent arm c of the switch-operating rod C and constitutes the medium through which the switch is operated.

15 J is a bent lever-arm which when lifted engages with the teeth of the escapement-wheel and locks it against motion. This arm extends out under the track, is fulcrumed at J' , and is connected to a depressible locking-rail R , which is arranged to be pressed upon 20 by the car-wheels to lift the end of the arm J in the box and lock the escapement mechanism.

The rock-shaft bearing the pendulum has 25 its back bearing vertically adjustable, so that the said shaft can be lifted to take its lugs g g' instantly away from the escapement-wheel, as shown in dotted lines in Fig. 2, and allow the motor mechanism to act at once without 30 waiting for the escapement mechanism to act through its regular period of time. To accomplish this, said bearing is slotted (see Fig. 6) and arranged above a hinged arm I , which is made to do the lifting through a vertical 35 rod I^2 , which at its lower end connects with an arm K' of a rock-shaft K , which is provided with bearings k along the track and has on the opposite side from the arm K' another shorter arm K^2 , Fig. 1, with a shoe k^2 on its end, which 40 is adapted to be pressed down by the car-wheels of the train on the main track.

In the bottom of the box and running transversely beneath the arm K' and the lever J there is a short treadle-lever L , which extends 45 through the side of the box and is provided with a foot-piece l to be depressed by the foot, and its effect when so depressed is to lift arm J and lock the escapement and simultaneously to lift arm I and disconnect the escapement. 50

M is a visible signal, of ordinary construction, having vanes with red and white sides, designed to show open or closed position of the switch. At night a red and white light is 55 used. This signal is fixed on a vertical rock-shaft m , which at its lower end has a pair of arms m' , Fig. 7, that are rocked by the movement of the arm c of switch-operating rod C .

The operation of my device as so far described is as follows: To open the switch and connect the siding, the treadle L is first depressed by placing the foot on the rest l . This throws up lever-arm J and locks the escapement-wheel, and at the same time throws up arm K' , vertical rod I^2 , pivoted arm I , and pendulum-shaft G , breaking the connection of the escapement at g , as shown in dotted

lines, Fig. 2. The switch-lever E' is now turned back in the direction of the arrow, Fig. 3. This action (see Fig. 7) winds up cord a 70 on drum E^3 , putting spring b under tension, and the cam E^4 , bearing against arm c , throws the switch-rod C and switch to the left, Figs. 1, 2, and 7. At the same time semicircular gear E^2 goes into engagement with the small 75 gear f and rotates the escapement-wheel F' backward. Treadle L is now released. This drops pendulum-shaft G , so that its escapement is connected at the point g and the locking-arm J is allowed to drop away from the 80 escapement-wheel. The power of the spring b is now free to rotate drum E^3 , gear E^2 , gear f , escapement-wheel F' , and the pendulum-shaft G , with pendulum H , begins to rock, and continues to rock until semicircular gear E^2 85 passes out of engagement with the small gear f , and then the rapid return of the drum E^3 and semicircular gear E^2 throws the switch-rod C and switch to its closed position even if the switchman has forgotten to do so. The 90 means by which this is accomplished by the unwinding of the motor is as follows:

The end of the semicircular gear E^2 , Fig. 7, as it nears the end of the stroke strikes against the end of horizontal lever S' , fulcrumed at s 95 in the bottom of the box to move in a horizontal plane, and as the other end of the lever is jointed to the switch-operating rod C it will be seen that the impact of the segmental gear E^2 in moving backward causes a 100 motion in the direction of the arrows, which throws the switch-rod C to the right and closes the main-line rails.

On the end of lever S' is fulcrumed a lever-detent n , which when the switch is adjusted 105 onto the siding-rails catches against a lug n' (see Fig. 2) in the bottom of the box and locks the parts in this position until automatically released. When this is to happen, a pin o on segmental gear E^2 rides on the end of detent n (see Fig. 7) and throws its opposite end above the retaining-lug n' , as shown in Fig. 2.

At the end of the segmental gear E^2 there is a pivoted and spring-seated section of teeth 115 t , forming a break in the continuity of the gear. The object of this is to lead the gear-teeth on the pinion f above it when it reengages the same without allowing the cogs to jam. 120

At the beginning of the section t the cogs are omitted, as seen at t' . This allows the slide-rails to move at once when time has expired for the switch to remain open. If it were not for the skip in the cogs, the slide-rails 125 would have to be moved slowly, and if a train should use the main line while these rails were being moved it would be wrecked.

Ordinarily after the switchman has adjusted his switch-lever E' to open the switch 130 he will immediately close it by simply putting his foot on treadle l , which prevents the escapement from acting; but if he forgets to do this the switch through its motor and es-

capement will after a predetermined time close itself. The period of time through which the switch is made to close is predetermined and is rendered variable to suit the requirements of the case by moving the adjustable weights h on the pendulum H in or out from the center. The shorter the stroke of the pendulum the more rapidly the escapement runs down and the sooner the switch is closed.

In case a train should come over the main track during the period within which the escapement is acting the wheels of such train press down shoe k^2 and by rocking shaft K in its bearings k lifts rod I^2 and by disconnecting the escapement mechanism allows the motor to run down instantly and instantly closes the switch. One of the bearings k is in rod C , which causes the shoe k^2 to come in range of engagement with the car-wheels only when the switch is open, as shown in dotted lines, Fig. 1.

To hold the escapement from running down while a train is on a switch, and thus keep the switch open until the train is off the switch, the depressible rail R under the pressure of the cars holds the locking device J up into contact with the escapement-wheel, as in Fig. 2, and thus renders it inoperative until the train is off the switch.

On the shaft E , outside the box, there is an index-hand N (see Fig. 4) on the opposite end from the hand-lever, which index-hand points to a graduated arc scale showing how nearly the switch is to being turned off. The hand-lever E' coöperates with a similar graduated scale on its side for the same purpose. In the side of the box adjacent to the hand-lever there is also a spring-lock O , Figs. 3 and 4, which is provided with a bolt adapted to engage with the shaft E of the hand-lever, so as to automatically lock the switch against being tampered with by unauthorized persons.

In making use of my invention I would state that I do not confine myself to the particular construction shown and described, as various modifications might be made without departing from my invention. Instead of using a spring-motor for actuating the time-escapement it is obvious that a weight-motor, as shown in dotted lines, Fig. 7, or any other form which is set into action by the opening of the switch might be used.

Having thus described my invention, what

I claim as new, and desire to secure by Letters Patent, is—

1. A self-closing railway-switch, comprising a motor set into action by the opening of the switch, a time-escapement, and means for causing the motor to act upon the switch and close it at the expiration of its time period substantially as and for the purpose described.

2. A self-closing railway-switch, comprising a motor set into action by the opening of the switch, a time-escapement, means for causing the motor to act upon the switch at the end of the time period, and a device arranged along the road-bed to be pressed down by a train, said device being connected to the time-escapement to render it inoperative and instantly close the switch substantially as and for the purpose described.

3. A self-closing railway-switch, comprising a motor set into action by the opening of the switch, a time-escapement, means for causing the motor to act upon the switch at the end of the time period, and a device arranged beside the road-bed of the siding to be normally pressed upon by cars on the switch said means being provided with a locking device to hold the escapement while the cars are on said switch substantially as and for the purpose described.

4. A self-closing and self-locking railway-switch comprising a motor set into action by the opening of the switch, a time-escapement, means for causing the motor to act upon the switch and close it at the expiration of its time period, means for locking the switch open, and means for automatically unlocking the same in closing substantially as and for the purpose described.

5. A self-closing railway-switch, comprising a rotary spring-actuated shaft bearing cam E^4 and segmental gear E^2 , a switch-actuating rod C having connection with and set by said cam, a superposed shaft with pinion and escapement wheel, an escapement-shaft with pendulum and escapement-lugs or pallet, means for lifting the escapement-shaft from its wheel, and means for causing the backward motion of the spring-shaft to operate on the switch-rod to close the switch substantially as shown and described.

RUFUS FRANKLIN CARNES.
